NEWTON F. FONER, OF PITTSBURGH, PENNSYLVANIA.

ENGINE.

Application filed August 20, 1925. Serial No. 51,419.

The device forming the subject matter of this application is an internal combustion engine of the two cycle type, in which the cycle work is divided. One revolution, two strokes complete a cycle. The temperature and pressure of the charge (air plus combustible) or air alone being readily controlled, it being possible to vary and adjust the character of the mixture, and the danger of premature explosion being eliminated.

The invention has as one of its objects, the provision of an engine embodying a set of cylinders for suction and compression, wherein, as the name indicates, the charge or air is drawn in and compressed before it is passed over to the combustion cylinders.

By forcing a cooling medium first through the compression jacket and then through the combustion jacket, the medium cools the charge in the compression cylinder and then is passed to the combustion cylinder.

It is also arranged to carry the cooling medium first about the combustion cylinders and then about the compression cylinders, the cooling medium functioning at a higher temperature than that which exists in the compression cylinder when the flow is in an opposite direction. The compression cylinders do now act as a heat-interchanger on the cooling medium and absorb part of the B. t. u.'s before the same has passed to the recirculating tank. The temperature of the compression cylinders in view of the foregoing, can be regulated to suit the ignition temperature of the fuel, the B. t. u. in the combustion cylinders being increased, by charging it with a hot combustion product or combustion air as the case may be, those parts of the B. t. u.'s which would otherwise be wasted, are being utilized. The construction, moreover, is such that the area of the cooling tank or radiator may be reduced, because the compression cylinders operate as cooling members.

In the case where fuel explodes at a very low temperature or from other operating reasons, it is desired to operate the engine on a constant pressure basis, then we heat the combustion air in the compression cylinder with the hot circulation fluid from the combustion cylinder and mix the charge in the combustion cylinder after closing of valve #27.

A further object of the invention is to im-

prove the means for actuating the valves and for bringing about a proper timing of the valves.

The invention aims to provide an engine which will operate in a satisfactory and efficient way with widely different sorts of fuels, the use of no one particular fuel being requisite.

A further object of the invention is so to construct the engine that the various movements will conform to the crank shaft motion in such a way that a compact engine will result.

Further, the invention does not require the use of cam shafts and other details which produce complications in manufacture and in operation. The device is self-balanced and requires no fly wheel, the engine being capable of use in connection with an airplane, although it is not confined to that use, and may be employed for any purpose to which it is adapted, it being observed that the engine will operate without an expensive or cumbersome support.

It is within the province of the invention to improve generally and to enhance the utility of, devices of that sort to which the invention appertains.

In the drawings, one form has been shown, by way of illustration, merely, but it is to be understood that the invention may be embodied in many other forms, and that a mechanic, working within the scope of what is claimed, may make such changes as his skill may suggest, without departing in anywise from the spirit of the invention.

In the accompanying drawings:—

Figure 1 shows in section, an engine wherein the invention has been embodied, parts appearing in elevation; Figure 2 is a sectional elevation taken in a plane about at right angles to the cutting plane in Figure 1; Figure 3 is a sectional view of the cam mechanism; Figure 4 is a sectional view of the cam mechanism, taken in a plane about at right angles to the cutting plane in Figure 3.

In carrying out the invention, there is provided a frame 1, which may be of any desired sort. As shown, but not of necessity, the frame 1 embodies a tubular crank case 2 having openings 3 and 4 about its periphery. A shaft 5 extends longitudinally of the crank case 2 and is journaled for rota-

tion therein, the shaft having cranks 6 and 7, located within the case 2. As has been stated hereinbefore, the engine is so constructed that it can be used on airplanes, and the shaft 5, therefore, has been shown, in Figure 1, as carrying a propeller 8—although the engine may be for any purpose for which it is adapted.

Compression cylinders 9 are mounted on 10 the crank case 2 in radial relation thereto, and there may be as many or as few of these cylinders as the taste of the designer, or the proposed use of the engine, may demand. The compression cylinders 9 have jackets 15 10 for the cooling medium, which may be water, or anything else suitable for the purpose. Pistons 11 are mounted for reciprocation in the cylinders 9, and are connected by rods 12 with the crank 6, the rods operating through the openings 3.

Combustion cylinders 14 are mounted on the crank case 2, there being one of the cylinders 14 for each of the compression cylinders 9. The combustion cylinders have 25 jackets 15. Pistons 16 are mounted for reciprocation in the combustion cylinders 14 and are connected by rods 17 with the crank 7, the rods 17 operating through the openings 4.

30 For convenience in tracing out the flow of the cooling medium, the jackets of certain of the compression cylinders have been designated, in Figure 2, by the characters 10^a and 10^b, the corresponding compression cylinders being designated by the characters 9^a and 9^b. A pipe for carrying the cooling medium is designated by the numeral 18 and communicates with the jacket 10^a of the cylinder 9^a, that jacket being connected to the next jacket 10, the remaining jackets 10 being connected, and the final jacket 10 being connected to the jacket 10^b by pipes 19 or their equivalent. A pipe 20 connects the jacket 10^b with the jacket 15 of the combustion cylinder 14 which is opposite to the cylinder 9^a, the jackets of the combustion cylinders being connected by pipes 21 or the like, a pipe 22 communicating with the jacket of the combustion cylinder which is opposite to the compression cylinder 10^b.

50 The numeral 28 marks air strainer containing also a fuel inlet communicating with a conduit 24 which, in its turn, communicates with the compression cylinders 9 at their outer ends, the passage of the fuel from the conduit 24 into the outer ends of the compression cylinders 9 being under the governance of spring-closed inlet valves 25. Communication is established between each compression cylinder 9 and the corresponding combustion cylinder 14 through a passage 26, under the governance of a spring closed transfer valve 27. The exhaust conduit is marked by the numeral 23 and communicates with the combustion cylinders 14, the pas-

sage of the exhaust from the cylinders 14 into the exhaust conduit 23 being under the control of spring-closed exhaust valves 29.

The transfer valves 27 and the exhaust valves 29 are operated by levers 30 fulcrumed intermediate their ends at 31 on the frame of the engine, and to the outer end of each lever 30, a link 32 is pivoted, the link being pivoted to a lever 33 fulcrumed intermediate its ends at 34 on the engine frame, 70 the lever being pivoted to an arm 35. Each inlet valve 25 is controlled by a lever 36 fulcrumed at the point indicated at 31, the lever 36 being actuated by such parts as those shown at 32—33—35 in Figure 1, and 80 hereinbefore described.

The levers 36 and 30 are actuated from the crank shaft 5 by a cam mechanism shown in Figures 3 and 4, although the levers might be operated otherwise. As shown, the cam mechanism includes a hub 37 and a disk 38 on the shaft 5, a lateral annular rib 39 and a rim 40 being secured to the disk 38, the parts 35 having rollers 41 or the like which operate between the hub 37 and the rib 39, 90 the corresponding arms for the levers 36 carrying rollers 42 which operate between the rib 39 and the rim 40.

The charge or combustion air is sucked in through the inlet 28 and the conduit 24, 95 enters the compression cylinders 9, the inlet valves 25 being opened. The valves 25 close, the fuel is compressed by the pistons 11 in the cylinders 9, the valves 27 open, admitting the compressed fuel into the cylinders 14, the valves 27 close, the fuel is compressed in the cylinders 14 by the pistons 16, the charge is fired in any suitable way, the pistons 16 do their work, the valves 29 open, and the exhaust leaves 105 by way of the exhaust conduit 23.

The operation of the valves is simple. Taking the valves 27 and 29 as typical, these valves are actuated by a train of elements comprising the lever 30, the link 32, the lever 33, the part 35, the projections or rollers 41, and the cam mechanism shown in Figures 3 and 4, the cam mechanism being so designed that it will operate all of the valves in properly timed relation.

115 The cooling medium, passing through the parts 18, 10^a, and 19, moves in a circuit beginning with the jacket 10^a of Figure 2, and ending with the jacket 10^b of Figure 2, the medium thus being caused to circulate 120 through the jackets of the compression cylinders 9. The cooling medium then crosses over through the pipe 20, and makes a circuit through the jackets of the combustion cylinders 14, the cooling medium leaving by way of the pipe 22. By any suitable mechanism, not shown, the direction of flow of the cooling medium may be reversed. If the cooling medium passes first through the jackets of the compression cylinders 9 125 130

the charge or the combustion air will be cooled to any desired degree, because the cylinders 9 tend to equalize its temperature with the cooling medium. By passing the cooling medium first through the jackets of the combustion cylinders 14 and then through the jackets of the compression cylinders 9, the compression cylinders are heated, that is the charge or combustion air, to any desired temperature with the B. t. u.'s contained in the medium on its return from the combustion cylinders 14. It is possible, therefore, to regulate the temperature in the compression cylinders 9 to accommodate fuels having different firing points of temperature. A wide variety of fuels may be used, and the operator can cool or heat up the charge or combustion air, in the cylinder to suit operating conditions.

The engine can also be operated entirely air cooled or partly air cooled. Since the compression cylinders are not necessarily of the same volume, the quantity of the air supply is predetermined by the volume relations of the cylinders.

The work of the combustion cylinders is well regulated through the control of the temperature and pressure of the charge in the compression cylinders.

What is claimed is:—

1. An internal combustion engine comprising a compression cylinder and a combustion cylinder, a transfer valve controlling the flow from the compression cylinder to the combustion cylinder, an intake valve controlling the flow to the compression cylinder, an exhaust valve controlling the flow from the combustion cylinder, pistons operating in the cylinders, a crank shaft, pitmans connecting the pistons with the crank shaft, means for operating one of the valves, and means for operating the other two of the valves, both of said means being operated independently, but in properly timed relation, by the crank shaft.

2. An internal combustion engine comprising a compression cylinder and a com-

bustion cylinder, a transfer valve controlling the flow from the compression cylinder to the combustion cylinder, an intake valve controlling the flow to the compression cylinder, an exhaust valve controlling the flow from the combustion cylinder, pistons operating in the cylinders, a crank shaft, pitmans connecting the pistons with the crank shaft, levers fulcrumed intermediate their ends on the frame of the engine, the outer end of one lever operating the intake valve, the outer end of the other lever operating the transfer valve, and mechanism for connecting the inner ends of both levers operatively with the crank shaft, the exhaust valve cooperating with said other lever at a point between said mechanism and the fulcrum for that lever.

3. A device of the class described, comprising a tubular crank case, compression and combustion cylinders arranged in pairs around the crank case and carried thereby, pistons operating in the cylinders, a shaft journaled in the ends of the case and having cranks located within the case, pitmans connecting the cranks with the cylinders, inlet valves for the compression cylinders, exhaust valves for the combustion cylinders, transfer valves controlling the flow from the compression cylinders to the combustion cylinders, all of the valves being located at the outer ends of the cylinders, means for operating the valves, embodying levers fulcrumed at the outer ends of the cylinders and extended inwardly toward one end of the crank case, a cam disk on the shaft and located at said end of the crank case, other levers fulcrumed intermediate their ends on said end of the crank case, links connecting the inwardly extended ends of the first-specified levers with the said other levers, and arms pivoted to said other levers and cooperating with the cam disk.

In testimony that I claim the foregoing as my own, I have hereto affixed my signature.

NEWTON F. FONER.
